UNITED STATES PATENT OFFICE.

GEORGE W. HALL, OF WASHINGTON, DISTRICT OF COLUMBIA.

TYPE-WRITING MACHINE.

SPECIFICATION forming part of Letters Patent No. 364,343, dated June 7, 1887.

Application filed April 24, 1884. Serial No. 129,101. (No model.)

To all whom it may concern:

Be it known that I, GEORGE W. HALL, a citizen of the United States, residing at Washington, in the District of Columbia, have invented 5 certain new and useful Improvements in Type-Writing Machines, of which the following is a specification, reference being had thereto to the accompanying drawings.

My invention relates to that class of type-writing machines employing a movable type-carrier; and its object is to provide a machine of this kind which will be simple and inexpensive in construction and efficient in operation, and to secure perfect alignment and spacing 15 of the letters.

In the accompanying drawings, Figure 1 is a top plan (partly broken away, on line 1 1, Fig. 3, to show the underlying mechanism) of a machine embodying my invention. Fig. 2 is a 20 vertical section of the same on the line 2 2, Figs. 1 and 3. Fig. 3 is a transverse section on the line 3 3, Figs. 1 and 2. Fig. 4 is an enlarged face view of the type-carrier, and Fig. 25 5 a section of the same. Fig. 6 is a detail view of the ribbon mechanism, and Figs. 7, 8, and 9 detail views of the mechanism for operating the impression cylinder.

A indicates the sides or standards of the frame-work of the machine, which will be of 30 cast-iron or other suitable material.

A' is the base of the frame-work, A² an elevated platform supported by the sides A, and A⁴ the top or cover, which will be the key-board.

35 B is a rock shaft or bar pivoted to the sides A. This shaft or bar B is provided with a series of fingers, b, extending beneath the key-board.

C is the type-carrier connected to arms c, 40 the extremities of which loosely embrace the bar B, so as to move freely longitudinally thereof. To the bar B is secured an arm, b', the outer end of which enters a slot in a bar, c', connecting the arms c, or forming part of 45 the type-carrier C, said outer end of the said arm b' being preferably provided with an anti-friction roller, l². The arm b' thus serves as a rigid support for the type-carrier C relative to the bar B, so that said carrier will move vertically when the said bar is rocked, while the 50 loose connections of the type-carrier with the

said bar, by means of the arms c, roller b', and slotted bar c', will admit of a free horizontal movement of said type-carrier. Thus it will be evident that said carrier will be capable of 55 a universal movement in a vertical plane, so as to bring any of the types carried thereby into a desired position.

The horizontal movements of the type-carrier are imparted thereto from a rocking shaft 60 or bar, D, pivoted to lugs or supports D' on the base A' and provided with a series of fingers, d. Said bar D is also provided with a rigid arm, d', connected by a link, d², with one of the supporting-arms c of the type-carrier, 65 so that any rocking movement of the shaft D will cause a corresponding horizontal movement of the type-carrier.

The rocking finger-bars B and D are actuated by the operator by means of a series of 70 vertically-sliding keys, E, having buttons of the usual form at their upper ends, said keys being guided vertically in recesses in the platform A² and key-board A⁴.

The keys E, excepting those in the upper and left-hand rows, Fig. 1, are arranged at the intersection of the fingers b and d, so that both of the finger-bars may be moved by any one of these keys, excepting those in the upper and left-hand rows, Fig. 1, which will (with the exclusion 75 of the corner key at the intersection of these two rows, which moves neither finger-bar) each move but one of the said finger-bars. The keys E preferably engage the fingers b and d by flat pointed projections e, which are more 80 conducive to a delicate and steady movement than a larger contact-surface. The rocking finger-bar B is moved in opposition to the movement imparted thereto by the keys E by a retracting-spring, b², connected to an arm, 85 b³, on said bar and to the frame of the machine, and the finger-bar D is similarly moved by a spring, d², connected to one of the fingers d and to the frame.

As the keys E are arranged at varying distances from the axes of the finger-bars B and D, it follows that equal vertical movements of the said keys will result in varying movements of the type-carrier. Thus, supposing the parts to be so proportioned that a vertical 90 movement of one-half an inch of any of the keys in the right-hand row, Fig. 1, would cause 95

a rocking movement of ten degrees to the finger-bar B, it follows that a similar movement of any of the keys in the rows farther to the left would cause a lesser rocking movement of said bar. According to well-known mathematical rules the fingers *b* and *d*, arranged as shown, would have to be unequally spaced on the bars B and D, by arranging the fingers *d* farther and farther apart toward the left in Fig. 1, 10 and the fingers *b* farther and farther apart toward the top in said figure, to secure a uniform variation of movement to said bars from the keys in the different rows; but as this would require an unequal spacing of the keys, 15 and as it is desirable to space the latter uniformly, the uniform variation above referred to is preferably secured by "lost motion," which results from constructing the keys so that they may have more or less vertical movement before their projections come in contact with the fingers *b* or *d*. This lost motion is, however, so very slight practically that it need not be taken into consideration; but it will be greatest with the keys which are farthest removed from the axes of the bars B and D. 25

The downward movements of the fingers *b* and *d*, and consequently of the keys E, are limited by a series of pivoted stops, F, arranged to be brought into contact with cross- 30 rods *f*, passing through the fingers *b* and *d*. The stops F are carried by shafts *f'*, pivoted to brackets *a'*, attached to the base A' and platform A², respectively. The brackets *a'* on the platform A² are insulated therefrom, for a purpose which will presently be explained. The shafts *f'* are provided with a series of arms, *f''*, arranged beneath the pins *e'* on the keys E, either the said keys or the pins *e'* (preferably the former) being of insulating material. 35

40 Springs *f''* (preferably coiled torsional springs, as shown) hold the arms *f''* in contact with the pins *e'*, which latter thus serve to support the keys E and to raise said keys after they have been depressed. The upward movement of 45 the keys E will be limited by suitable stops, as by forming said keys with shoulders abutting against the under side of the key-board. This construction is shown in Fig. 2, in which the keys E are represented as being larger below the key-board A⁴ than they are above it, the tops of the enlarged portions of said keys forming the shoulders just referred to. 50

From the foregoing it will be readily understood that when any one of the keys is depressed its pin *e'*, acting on the adjacent arm *f''*, will turn one of the shafts *f'*, bringing the stop F thereon into the path of one of the rods *f*, so that when said rod strikes the stop the further descent of the fingers will be arrested. 55

60 All of the keys which engage both sets of fingers *b* and *d* will of course operate a stop for each set of fingers, and will consequently be lifted by two arms *f''*, while the downward movement of the keys in the upper and left-hand rows, Fig. 1, will be limited by other stops—as, for example, small cross-pins *e''*—which will impinge against the upper surface of the plat- 65

form A². The keys in the left-hand row, Figs. 1 and 3, will be lifted in the same manner as the other keys; but the stop F, not being required on the left-hand shaft *f'*, Fig. 3, will be omitted therefrom. 70

The types *c'* carried by the type-carrier C are preferably arranged to be driven horizontally against the impression-cylinder G by a 75 hammer, H, carried by a jointed vibrating lever, H', the types being retracted by small spiral springs *c''*. The lower part, *h*, of the lever H' consists of an armature of an electromagnet, I, and to the upper part, *h'*, of said lever, just above the joint thereof, is attached a light spring, *h''*, for retracting said lever. When the electrical circuit in which the magnet I is connected is closed said magnet will attract its armature, and the sudden movement of the lever H' toward the magnet will give sufficient impetus to the hammer H to drive the particular type which may be in front of it against the impression-cylinder, and thus print the letter desired. To effect this result it will be understood that the lever H' bends at its joint to permit of the proper forward movement of the hammer, by its momentum after the armature is stopped by contact with the magnet, the joint being 95 constructed like an ordinary hinge or knife-blade joint, so that the backward movement of the upper part, *h'*, of the said lever will be limited relatively to the lower part, *h*, thereof. As the circuit will be broken almost the instant that it is closed, (as will be explained presently,) the magnet I will cease to attract its armature, and the lever H' will be quickly retracted by the spring *h''*, this action of the spring being assisted by the natural rebound 105 of the hammer.

The shafts *f'* on the platform A² are electrically connected together, and are also connected by a conductor, 2, to a battery, as 1. An electric current from said battery is thus free to pass to the shafts *f'* and their attached stops F, and when, by the depression of the fingers *b*, the cross-rods *f* are brought into contact with said stops, the electric circuit will be closed, and the current will pass through the 110 fingers *b* and bar B to the frame of the machine, and through a conductor, 3, attached thereto, to the magnet I, passing from the latter through a conductor, 4, back to the battery. 115

As the keys in the left-hand row in Fig. 1 do not operate the fingers *b*, the circuit in which the magnet I is arranged is closed by the keys in the said row in the following manner: A rock-shaft, *f''*, similar to the shafts *f'*, and 120 electrically connected with the latter, and thus with the battery 1, is provided with a series of arms, *f''*, arranged to be engaged by pins *e''* on the keys E. When any one of said arms is engaged by one of the pins *e''* the shaft *f''* will be 125 partially rotated against the stress of its retracting-spring, and an arm or stop, *f''*, on said shaft will be forced into contact with the metallic platform A² or a pin, *a'*, thereon, thus 130

closing the circuit and energizing the magnet I, so that it will operate its armature and the hammer H.

It will be understood that the arm f^6 will 5 strike the platform A² or the pin a^5 to complete the circuit at the instant that a key of the said left-hand row has descended the proper distance to give the requisite movement to the finger-bars B and D to bring the type 10 responding to the key depressed into position to be struck by the hammer H.

The impression-cylinder G is mounted on a carriage, J, movable horizontally on a supporting-bar, K, carried by arms k', suitably 15 sustained by the frame of the machine. The cylinder G may thus readily be turned up by the operator when it is desired to examine the printing. The carriage J is moved forward by a spring, j, and its movement, as each letter 20 is printed, is controlled by an escapement, L, engaging a rack, j', on said carriage, said escapement having a metallic contact-piece, l, constituting an armature for an electro-magnet, M.

25 The magnet M is connected with the battery 1 by a conductor, 5, and by a conductor, 6, to a post, 7, insulatingly attached to the base A' of the machine. A contact-arm, f', attached to a rock-shaft, f⁸, is normally held against the 30 post 7, so that the current can pass through said shaft and a conductor, 8, to a contact-pin, 9, insulatingly attached to one of the sides A. To the arm d' of the bar D is insulatingly attached a contact-pin, d³, which is 35 connected by a conductor, 10, with the battery 1. As the circuit just described is normally closed, the armature l is normally held in contact with the magnet M; but the instant that the circuit is broken the armature will be 40 withdrawn from the magnet by the spring l', thus operating the escapement L and permitting the spring j to move the carriage J half the length, horizontally, of one of the teeth of the rack j', and when the circuit is again 45 closed the armature will be restored to its normal position, again permitting the carriage to move half the length of one of the said teeth.

The downward movement of any one of the 50 keys E (excepting those in the upper row in Fig. 1) will move the finger d, and consequently the finger-bar D and its attached arm d', causing the latter and the contact-pin d³, carried thereby, to recede from the contact-pin 9, and thus break the circuit in which the magnet M is connected. With the keys in the 55 upper row, Fig. 1, the circuit is broken by the movement of the contact-arm f' on the rock-shaft f⁸ away from the post 7, said shaft being partially rotated when any one of the 60 keys in the said row is depressed.

It will thus be apparent that the circuit in which the magnet I is connected is normally open, while the circuit of the magnet M is 65 normally closed. As the parts are so arranged that the circuit of the latter magnet will be broken at the commencement of the downward

movement of any one of the keys E, while the circuit of the magnet I is only closed at the termination of such downward movement, a 70 short interval will occur between the breaking of one circuit and the closing of the other. From this it results that the armatures of the said magnets and the devices actuated thereby will operate successively. 75

In order to space the words it is necessary that the carriage J should receive an additional movement, which is provided for by spacing-keys E', arranged at either side of the machine for the convenience of the operator. 80 Small springs a⁴, insulatingly attached to the base A', are arranged to form part of the conductors 6 and 8, respectively. Each of the keys E' rests on one of the springs a⁴, so that a slight depression of either of the said keys 85 will separate the springs from their contact-pieces a⁶, and thus break the electric circuit of the magnet M and operate the escapement L, to permit of the forward movement of the carriage J, in the manner before described. 90

The carbon or inking ribbon N is carried by two spools, N', secured to hollow shafts n, turning on spindles n', fixed to a frame or platform, N². Each of the shafts n is provided at its lower end with a ratchet-wheel, n², and a 95 gear-wheel, n³, the former being secured to the shafts and the latter turning loosely thereon. Spring-actuated pawls n⁴ connect the gear-wheels n³ with the ratchet-wheels n², so that said gear-wheels will be free to rotate independently of the shafts when turned in one direction, but will be connected with and will turn said shafts when rotated in the opposite direction. 100

On a swinging lever, n⁶, is mounted a gear-wheel, n⁵, adapted to engage a rack, j', on the carriage J. The lever n⁶ may be adjusted so as to engage the gear-wheel n⁵ with either of the wheels n³, and the said lever may then be secured in place by the set-screw n⁷, passing 110 through the outer end of the said lever and impinging against the platform N², or by other means, as by a projection on said lever engaging a recess in said platform. As the carriage J moves intermittently forward the rack 115 j' thereon will turn the gear-wheel n⁵, which, being in engagement with one of the wheels n³, will rotate the corresponding spool-shafts, n, and slowly wind the ribbon on the spool carried thereby, drawing it from the other spool. 120 When the end of a line has been reached and the carriage is returned by the operator, the gear-wheel n³, which is in connection with the rack j', through the gear-wheel n⁵, will turn loosely on its shaft, the pawl n⁴, pivoted there-to, riding freely backward over the teeth of its ratchet-wheel n². After the ribbon N has 125 been wound upon one spool, N', the screw n⁷ will be loosened and the lever n⁶ adjusted to bring the gear-wheel n⁵ into engagement with the other of the gear-wheels, n³, thus reversing the movement of the ribbon, which will then be wound on the other spool. 130

A guard plate or frame, O, preferably of

thin metal, and provided with an opening, o , for the type, is interposed between the type-carrier C and the impression-cylinder G. This plate or frame serves to keep the ribbon from smearing the paper being printed, and also as a means for engaging the spools to move the latter on their shafts, for the purpose of adjusting the ribbon vertically to bring successive portions thereof before the type. Said plate or frame O is provided with flanges o' , between which the spools are arranged, and also with threaded pins o^2 , projecting through cam-slots p of arms P, secured to a rock-shaft, p' , pivoted to the platform N². Set-nuts o^3 , adapted to the threaded pins o^2 , serve to hold the frame O and arms P in any position to which they may be adjusted. When it is desired to adjust the ribbon, the nuts o^3 are loosened and the arms P turned with their shaft p' , thus raising or lowering the frame O, and consequently the spools and ribbon.

Journalled in the flanges o' of the frame O are two small rollers, o^4 , for guiding the ribbon and keeping it in proper alignment with the type of the type-form.

To the shaft of the impression-cylinder G is secured a ratchet-wheel Q, and on said shaft is loosely pivoted a pawl-carrying lever, R, normally held up by a spring, r , attached to the carriage J. A swinging lever, S, is pivoted to a post, T, adjustably secured to the frame K, on which the carriage J travels, said frame being connected with the frame of the machine, so that it is stationary relative thereto.

To the post T and lever S is attached a spring, t , having a tendency to swing the lever S toward the left in Fig. 8, the movement of said lever under the action of said spring being limited by a pin or stop, t' , which comes in contact with the frame K. The lower end of the lever S is arranged in the horizontal path of the lever R, which moves with the carriage J, so that when the said carriage is returned by the operator to its initial position after a line has been printed, the said lever R, moving toward the right in Fig. 8, will come in contact with the lever S, and, as the latter swings, the shoulder s^2 thereon will engage the said lever R and force the latter downward, causing the pawl carried by said lever to turn the ratchet-wheel Q and the impression-cylinder for the purpose of feeding the paper for a new line. When the carriage J again moves forward the levers R and S will be returned to their normal positions by their springs r and t , respectively.

To secure a variation in the spacing of the lines the lever S is provided with a series of holes, s , preferably elongated, as shown, and the pivot-pin t^2 with a flattened head. By turning said lever, or the pin t^2 , so that the flattened head of the latter will register with the elongated holes s , the lever S may readily be slipped off from the said pin and adjusted to a new hole, the end of the spring t being also slipped out of its hole in the lever and

placed in another hole. This vertical adjustment of the lever provides for more or less lost motion after the lever R comes in contact with the projection s' , before the shoulder s^2 of the lever S strikes the lever R, to operate the latter. Thus the spacing of the lines will be determined by the position in which the lever S is adjusted.

A set-screw, t^3 , serves to secure the post T to the frame K, and said post may be arranged in the path of and thus serve as a stop for the carriage J at its backward movement. By loosening said screw said post may be adjusted longitudinally of said frame, so as to provide for stopping the carriage J and automatically feeding the paper at different points, according to the desired length of the lines being printed.

A button, g , attached to the shaft of the impression-cylinder, affords means for turning the latter independently of the automatic line-feeding mechanism just described.

The operation of my machine will be readily understood from the foregoing description. When one of the keys E is depressed, the type-carrier will be moved into such position as to bring the type corresponding to the key which has been depressed in front of the hammer H, which position of the type may be termed its "printing" position. The instant the printing position is reached the circuit of the magnet I will be closed and the hammer will be caused to strike the type to make the impression. As the circuit will not be closed to operate the hammer until the type to be impressed is in exact printing position, and as the printing positions of all the types will be accurately predetermined by the mechanical structure of my machine, it follows that a perfect alignment of the letters will be secured.

The feeding of the carriage J, which transports the impression-cylinder and the paper, is effected by the breaking and closing of the circuit of the magnet M, in the manner heretofore described, and as said circuit cannot be broken or closed except at the proper instants, accurate spacing of the letters and words necessarily results.

Although I have shown my type carrier as being arranged to have a universal movement in a vertical plane, and the type as moving horizontally in said form, it will be understood that by changing the connections with the operating-keys, or by arranging said keys horizontally instead of vertically, the position of the type-form might be changed, so that it would have horizontal movements and the type vertical movements, without departing from the spirit of my invention. The electrical connections of the magnets I and M might also be somewhat different from those hereinbefore described without changing the results effected thereby.

It will also be understood that portions of my invention—as, for example, the ribbon and line feeding mechanisms—may be used without

the others, or in connection with type-operating mechanisms differing from that herein shown.

Having thus described my invention, I claim 5 as new and desire to secure by Letters Patent—

1. In a type-writing machine, the combination of a series of sliding keys, two rocking finger-bars arranged at right angles to each other, two sets of fingers, and a type-carrier 10 connected with said finger-bars and adapted to move in two different planes, substantially as set forth.

2. In a type-writing machine, the combination of a series of sliding keys, two rocking finger-bars, two sets of fingers, and a series of 15 movable stops operated by said keys and serving to limit the movements of said fingers, substantially as set forth.

3. In a type-writing machine, the combination of a series of sliding keys, a rocking finger-bar, B, having a series of fingers, b, a rocking finger-bar, D, arranged at right angles to the bar B and having a series of fingers, d, a type-carrier rigidly connected with the bar B, 25 so as to rock therewith, but adapted to slide freely longitudinally thereof, and connections, substantially as described, operated by the bar D, for sliding the type-carrier longitudinally of the bar B, all substantially as set forth.

30 4. The combination, with the keys E, of the finger-bar B, having fingers b and arm b', the type-carrier C, arms c, loosely embracing the bar B, slotted bar c', finger-bar D, having fingers d and arm d', and the link d', substantially as set forth.

40 5. The combination, with the sliding keys E, having pins e, the type carrier, the two rocking finger-bars, each having a series of fingers, and connections between said finger-bars and type-carrier, of the cross-rod f, the shafts f', having arms f'', the stops F, carried by said shafts, and the springs f'', substantially as set forth.

45 6. In a type-writing machine, the combination of a series of sliding keys, two rocking finger-bars, two sets of fingers attached to said bars, a type-carrier movable in two different planes, as described, a series of types supported by said carrier, a hammer for forcing said types against the impression-cylinder, an electro-magnet for operating said hammer, and an electric circuit in which said magnet is connected, adapted to be closed by any one of said keys when the type-carrier has been 50 moved into proper position for the hammer to strike the type, substantially as set forth.

70 7. The combination, with the type-carrier and the types carried thereby, of the jointed lever H', the hammer H, carried thereby, the electro-magnet I, and the retracting spring h'', substantially as set forth.

75 8. In a type-writing machine, the combination of a series of sliding keys, two finger-bars arranged at right angles to each other, two sets of fingers attached to said bars, an impression-cylinder, a carriage on which said cylinder is

mounted, a spring for moving said carriage forward, a rack-bar, an escapement for controlling the forward movements of said carriage, an electro-magnet for operating said escapement, and a circuit in which said magnet is connected, and which is broken when one of the said keys is moved, substantially as set forth.

70 9. In a type-writing machine, the combination, with the ribbon-spools, their shafts, and gear-wheels mounted on the latter, of a traveling carriage having a rack and a gear-wheel mounted on a movable axis and thus adapted to be shifted into engagement with either of the gear-wheels on the spool-carrying shafts, substantially as set forth.

75 10. The combination of the platform or frame N², the spindles n', fixed thereto, the hollow shafts n, ratchet-wheels n², loose gear-wheels n³, pawls n⁴, gear-wheel n⁵, lever n⁶, and carriage J, 80 having a rack, j², substantially as set forth.

85 11. In a type-writing machine, the combination, with the type-carrier, the type, the impression-cylinder, and the ribbon-carrying spools, of an adjustable plate or frame for the 90 said spools, a portion of said plate or frame being interposed between the type-carrier and the impression-cylinder and having an opening, and two rollers journaled in said frame and serving to keep the inking-ribbon in proper 95 alignment, substantially as set forth.

100 12. In a type-writing machine, the combination, with the ribbon-carrying spools and the frame O, provided with pins o², of the connected sectors P, having cam-slots in which said pins are arranged, substantially as set forth.

105 13. The combination, with the frame K, carriage J, impression-cylinder G, ratchet-wheel Q, and pawl-carrying lever R, of the spring t and the lever S, having a portion or projection, s', arranged in the path of the said lever R, and a shoulder, s'', adapted to positively engage and thus operate said lever R when the lever S has moved a certain distance, substantially as set forth.

110 14. The combination, with the frame K, carriage J, impression-cylinder G, ratchet-wheel Q, and pawl-carrying lever R, of the lever S, having a portion or projection, s', arranged in the path of the said lever R, and a shoulder, s'', the spring t, and the stop t', substantially as set forth.

115 15. The combination, with the impression-cylinder G, ratchet-wheel Q, and pawl-carrying lever R, of a swinging lever, S, connected with the frame of the machine and arranged in the path of the lever R, said lever S having a series of elongated holes for adjustment, the pivot-pin t', having a flattened head, the spring t, and the stop t', substantially as set forth.

120 125 In testimony whereof I affix my signature in presence of two witnesses.

GEORGE W. HALL.
